UNITED STATES PATENT OFFICE.

HENRY M. WILLIAMS, OF FORT WAYNE, INDIANA, ASSIGNOR OF ONE-FOURTH
TO FRANZ BURGER, OF SAME PLACE.

DESIGN FOR A CUP.

SPECIFICATION forming part of Design No. 29,814, dated December 20, 1898.

Application filed November 21, 1898. Serial No. 697,100. Term of patent 14 years.

To all whom it may concern:

Be it known that I, HENRY M. WILLIAMS, a citizen of the United States, residing at Fort Wayne, in the county of Allen and State of Indiana, have invented and produced a new and original Design for Cups, of which the following is a specification, reference being had to the accompanying drawings, forming part thereof.

10 Figure 1 is a plan view of a cup embodying my design, and Fig. 2 is a side view of the same.

The leading feature of my design consists in the shape or configuration of the bowl or body of a cup, and, as shown in Fig. 1, the bowl or body A presents an outline embracing four curves joined at their ends, forming what appear to be four rounded extensions *a*, with indentations *b* between them. These 15 extensions, as viewed from the side, have rounded outlines tapering toward the bottom of the body, as at *c*, where they converge to-

gether in the base B, and the body has the general appearance of a section of a sphere with indentations along the lines *b*. Connected to one of the extensions is a handle D, having a trefoil-shaped opening *d*.

The general appearance of the design presents a bowl or body embracing four curved and rounded extensions at the top merging 25 into each other as they extend downward, forming the bottom, and from one of the extensions projects a handle.

What I claim is—

The design for a cup or similar article, substantially as shown and described.

In testimony whereof I have signed my name to this specification in the presence of two subscribing witnesses.

HENRY M. WILLIAMS.

Witnesses:

GEO. K. TORRENCE,
J. BURGER.
